UNITED STATES PATENT OFFICE.

ISAAC H. TERRELL AND DANIEL L. TERRELL, OF KENT, OHIO.

MULTIPLE-FUSE PLUG.

Application filed January 5, 1922. Serial No. 527,213.

To all whom it may concern:

Be it known that we, ISAAC H. TERRELL and DANIEL L. TERRELL, citizens of the United States of America, and residents of 5 Kent, county of Portage and State of Ohio, have invented certain new and useful Improvements in Multiple-Fuse Plugs, of which the following is a specification.

This invention relates to fuse plugs, and 10 it has for its object the provision of a plug which embodies a plurality of fuses arranged in such manner that they may be successively disposed between terminals for completing the electric circuit.

15 A further object is to provide a fuse plug of the multiple-fuse type in which the fuses are carried by a member which may be readily rotated as occasion may require for successively positioning the fuses, and 20 which, following exhaustion of the fuses, may be easily removed, re-equipped with fuses and replaced by persons possessing little or no mechanical ability.

25 A still further object is to provide, in a device of the character mentioned, a dial and indicator by which one is enabled to accurately position the various fuses for insuring proper electrical contact, and which also serve to visually indicate at all times the 30 number of unused fuses remaining in the plug.

With these and other important objects in view, the invention resides in the features of construction, arrangement of parts and 35 combinations of elements which will herein-after be fully described, reference being had to the accompanying drawings, in which—

Figure 1 is a central longitudinal section of the invention;

40 Figure 2 is an outer end elevation;

Figure 3 is a similar view of the casing or body of the plug with the cap and fuse magazine removed;

Figure 4 is a lower end elevation of the 45 fuse magazine;

Figure 5 is an enlarged detail view in side elevation of the fixed terminal of the plug, removed;

Figure 6 is an enlarged plan view of the 50 pointer or indicator; and—

Figure 7 is a side elevation of a fragmentary portion of the magazine, showing a fuse and insulating strip mounted therein.

Referring to said drawings, 1 indicates

a hollow cylindrical casing which is open 55 at its outer end and which has a reduced inner end 1^a, the latter being exteriorly threaded and having mounted thereon a metallic shell 2 which constitutes one of the terminals of the plug and which is adapted 60 for assuming threaded engagement with a socket in the usual manner. Said casing 1 is formed of a suitable non-conducting material, preferably glass, and may have an integral wall or web 1^b extending transversely across it at or adjacent to the junction of the reduced end 1^a with the larger diameter thereof. The interior of said reduced end 1^a is filled with plaster of Paris or other suitable cementitious material 3 and, 70 when the wall or web 1^b is omitted, the outer end of said filler 3 may form the bottom of the chamber 4 located within that portion of the casing having the greatest diameter.

An insulating tip 5 of porcelain or other 75 appropriate material is fitted upon the inner end of the reduced end 1^a and is held in place by an axially disposed spindle 6 which is embedded in the filler 3 and extends into the chamber 4.

80 Mounted for rotation upon the spindle 6 is a metal sleeve-like member 7 forming a part of a fuse magazine, said sleeve carrying upon its outer end or having formed integral therewith a circular metal plate or disk 8, said disk having a plurality of regularly spaced radial slits 9 provided in its circumferential edge, the same being adapted for the reception of the outer end portions of a 85 plurality of fuses 10 which have their opposite end portions in like manner received by slits 11 provided in a disk 12 of fiber or other suitable non-conducting material which is suitably mounted upon the lower end of said sleeve 7. The opposite ends or 90 terminals 10^a of the vertically disposed fuses 10 are bent horizontally so as to overlie and seat upon the non-confronting faces of the disks 8 and 12 for frictionally maintaining the fuses against chance displacement.

95 Seated within the upper end of the sleeve 7 and preferably threaded into place to insure perfect contact with the sleeves and also to allow for adjustment is a metal stem 13 which has its lower end seated directly 100 upon the upper end of the spindle 6.

A spring contact 14 is suitably mounted at the inner end of the chamber 4 in posi-

tion to be successively engaged by the inner rearwardly directed terminals 10^a of the fuses as the magazine is rotated forward, said contact being suitably connected, as by 5 a wire 15, to the shell terminal 2.

A cap 16 is threaded upon the outer end of the casing 1, and preferably interposed between said cap and the magazine is a disk or washer 17 which may be made of

10 any suitable material. The outer face of said cap may constitute a dial, being provided with numbers or other appropriate indicia which, when said cap is properly positioned, indicate the positions of the fuses 15 in the underlying magazine. A pointer or indicator 18 removably mounted in a fixed position on the stem 13 is rotatable over the dial with rotation of the magazine and, assuming that it is initially positioned in register with the first of the numbers or other indicia carried by said dial, it will at all times visually indicate, or afford means for determining the number of fuses used and unused borne by the magazine.

25 A finger button 19 is detachably mounted upon the projecting outer end of the stem 13, the same affording convenient means whereby the magazine may be rotated for positioning the fuses.

30 When all fuses have been blown, or used up, the same may be replaced by new fuses upon removal of the magazine. Such removal may be readily effected by slipping the magazine out of the casing following

35 detachment of the finger button 19, indicator 18, cap 16 and washer 17, said parts being removed in the order named. An insulator strip 20 is preferably associated with each fuse 10, the same being seated against a 40 side of the fuse and having its ends also received in the slits 9 and 11. Obviously, said strips serve to shield unused fuses from injury when a fuse is blown.

45 As will be manifest from the foregoing description, the current for completing the electric circuit through the plug enters through the head terminal 6^a of the spindle 6 and passes thence through said spindle, the sleeve 7, the metal disk 8, the fuse 10 50 which then occupies seated relation to the

spring contact 14, said spring contact, and the wire 15 to the shell terminal 2.

The construction described not only provides a plug which is practically indestructible in that it may be refilled or re-equipped 55 with fuses when and as often as such may be required, but also a plug which is extremely simple and inexpensive to manufacture.

What is claimed is—

1. A multiple fuse plug comprising a non-conductive casing carrying a threaded shell terminal on its inner end, a spring contact located within said casing and connected electrically with said terminal, a spindle 65 having a portion disposed axially within said casing, and having its outer end forming the other plug terminal, a magazine mounted for rotation on said spindle, and a plurality of fuses carried by said magazine 70 and adapted through rotation of the latter to be successively positioned with an end in engagement with said spring contact, said magazine including a current-conducting sleeve embracing said spindle, a disk of 75 insulation material carried by the inner end of said sleeve, and a current-conducting disk carried by the opposite end of said sleeve, said disks having corresponding radial slits in which opposite end portions of said fuses are disposed, a cap-like closure for the outer end of said casing, and means projecting through said closure whereby said magazine may be rotated.

2. A rotatable magazine for multiple fuse plugs, comprising a central member, a metallic disk carried at one end of said member, a fibre disk carried at the opposite end of said member, said disks having spaced radial slits therein, and a plurality 80 of fuses arranged between said disks and having their opposite end portions slidable to and from seated positions in said slits.

In testimony whereof we affix our signatures in presence of two witnesses.

ISAAC H. TERRELL.
DANIEL L. TERRELL.
